PROCESS FOR COMBINING HYDROCARBON GASES WITH HYDROCARBON LIQUIDS

Filed Sept. 14, 1934

UNITED STATES PATENT OFFICE

2,104,285

PROCESS FOR COMBINING HYDROCARBON
GASES WITH HYDROCARBON LIQUIDSMalcolm P. Youker, Bartlesville, Okla., assignor
to Phillips Petroleum Company, Bartlesville,
Okla., a corporation of Delaware

Application September 14, 1934, Serial No. 744,073

5 Claims. (Cl. 196—78)

My new invention relates to chemically combining hydrogen, hydrogen gases, and hydrocarbon liquids.

An object of my new process is to provide a method by which hydrocarbon gases may be chemically combined with hydrocarbon liquids to form gasoline. Another object is to provide a method by which hydrogen may be combined with the heavier fractions of petroleum to enhance the value of these fractions for use as lubricants. Other objects of my new invention will be made apparent in the following specification.

My co-pending application Serial No. 12,681 discloses the use of molten sodium as a polymerization catalyst.

My new process will be fully understood from the following description taken in connection with the accompanying drawing. The drawing illustrates diagrammatically in side elevation a form of apparatus by which my new process may be carried out.

Referring to the drawing, the numeral 1 designates a furnace which is heated by a fuel burner 2. A tube 3 in which is mounted a pump 5 and a valve 6 leads from pump 5 through furnace 1 and into a tank 8. The extremity of tube 3 which projects into tank 8 is perforated. A pipe 9 in which is mounted a valve 10 and which is in communication with supplies of both hydrogen and hydrocarbon gas leads to pump 5. A tube 11 in which is mounted a pump 12 leads from tank 8 through furnace 1 and back into tank 8. A pipe 13 in which is mounted a pump 14 and which is in communication with a supply of hydrocarbon liquid leads into tube 11 at a point intermediate between pump 12 and furnace 1. A pipe 15 in which is mounted a pump 16 and which is in communication with a supply of molten, metallic sodium is connected into tank 8. A pipe 17 in which is mounted a valve 7 and a pump 18 leads from tank 8 into tube 3 at a point intermediate pump 5 and furnace 1. A drain pipe 19 in which is mounted a valve 20 leads from the bottom of tank 8. A pipe 21 in which is mounted a pump 22 and a valve 23 leads from the bottom of tank 8 into tube 3 at a point intermediate pump 5 and furnace 1. A pipe 24 in which is mounted a valve 25 leads from a point in pipe 21 intermediate valve 23 and pump 22 and thence into tube 3 at a point intermediate furnace 1 and tank 8. A pipe 26 leads from the top of tank 8 into the lower section of a bubbling type fractionating column 27. A pipe 28 in which is mounted a gas compressor 29 and a valve 30

leads from the top of fractionating column 27 into tube 3 at a point intermediate pump 5 and furnace 1. A pipe 30 in which is mounted a valve 31 and a pump 32 and which is in communication with a supply of cold hydrocarbon liquid leads into fractionating column 27 above bubble trays 33. A pipe 34 in which is mounted a valve 35 leads from the bottom of fractionating column 27. A vent pipe 36 in which is mounted a valve 37 leads from pipe 28. A pipe 39 in which is mounted a valve 40 leads from a point in pipe 28 intermediate valve 38 and compressor 29 through hydrogen activator 41 into tube 3 at a point adjacent tank 8. Hydrogen activator 41 may be of any conventional type such as means for passing hydrogen through a corona or through molten sodium or otherwise. As the activated hydrogen (H_3) is very unstable, the length of pipe through which this activated hydrogen will pass from activator 41 into tank 8 will be of such a length and size that only a small fraction of a second will elapse while hydrogen is flowing from activator 41 into tank 8. A pipe 42 in which is mounted a valve 43 is connected into pipe 17 at a point intermediate valve 7 and pump 18 and leads away from the apparatus.

This apparatus will be utilized to carry out my new process in the following manner:

Molten sodium will be delivered into tank 8 in sufficient quantity to submerge the perforated extension of tube 3 into tank 8. Heavy hydrocarbon liquid such as fuel oil or heavy distillate which has been obtained from crude oil will be continuously supplied through pipe 13 and pump 14 and thence through tube 11 and furnace 1 to the tank 8 in sufficient quantity to partially fill tank 8 and submerge the outlets from tank 8 into pipe 17 and tube 11. Hydrocarbon liquid will be withdrawn from the tank 8 through pipe 17 by means of pump 18 and discharged from the process to storage tanks through the pipe 42 and valve 43. Hydrocarbon liquid will be withdrawn from the tank 8 by means of pump 12 and will be delivered through tube 11 and furnace 1 back into tank 8, and this liquid so circulated through tube 11 will be heated in passage through furnace 1 to any desired temperature, thus maintaining the temperature of the oil contained in tank 8 at any desired point. Hydrocarbon gases or hydrogen or a mixture of these gases will be delivered through pipe 3 to pump 5 and will be forced by pump 5 through tube 3 and through furnace 1 wherein such gases will be heated to any desired temperature and these heated gases will then be delivered through the perforations in the extension of

tube 3 in tank 8. Any gas thus delivered through tube 3 into tank 8 will rise through the bath of molten sodium contained in tank 8 and thence through the body of oil contained in tank 8 and 5 will flow thence through pipe 26, fractionating column 27, and will be caused to flow by gas compressor 29 from the top of fractionating column 27 through pipe 28 into tube 3 and thence through tube 3 back into tank 8. Relatively cool hydro- 10 carbon liquid will be delivered through pipe 30 into the upper part of fractionating column 27 and will flow thence downward over bubble trays 33, contacting thereon the gases which will flow upward through fractionating column 27, and 15 this contact will result in scrubbing from these gases any liquid which may be evaporated in them, and the liquid thus flowed downward through fractionating column 27 will gather at the bottom of this fractionating column and will 20 be delivered thence through pipe 34 and valve 35 to be cooled and re-used or into storage tanks. A part of the liquid thus delivered through pipe 34 may be delivered directly into tank 8 through pipe 13 by means of connecting pipe 34 into pipe 13. 25 The quantity of oil held in tank 8 will be maintained constant by means of continuously withdrawing some of this material through pipe 47, pump 48, pipe 42, and valve 43. The process will be carried out under super-atmospheric pressure. 30 This pressure may be regulated by means of a back pressure valve 37 mounted in a gas vent pipe 36 which is connected into pipe 28 intermediate fractionating column 27 and gas compressor 29 and leads from the process. Any excess gas which 35 may accumulate within the apparatus may be vented from the process through pipe 36 and valve 37.

As a result of carrying out the above described operations, hydrogen, which has been heated in 40 tube 3 and activated by bubbling through molten sodium, may be contacted with the oil held in tank 8, and, being in an activated state, will thereupon combine with this oil. This combining hydrogen with the heavy fractions of petroleum will enhance their value as lubricants. The 45 rate at which oil is fed by pump 14 into and through tank 8 will regulate the degree to which such material is treated in passage through tank 8, the treated material being withdrawn from tank 8 as described by pump 18 and delivered 50 from the apparatus through pipe 42.

Several alternate methods of operation which 55 may be found useful are shown. Molten sodium may be withdrawn from the bottom of tank 8 and delivered by means of pump 22 through pipe 21 and thence through heating tube 3 in close contact with the hydrogen or gas flowing through tube 3. Valve 23 may be closed and valve 25 opened and molten sodium may then be delivered 60 by pump 22 from tank 8 through pipes 20 and 24 into tube 3 and thence into tank 8 accompanying other materials delivered through tube 3 into tank 8. Valve 38 may be closed and valve 40 may be 65 opened and the gas delivered from the top of fractionating column 27 may then be caused to flow through pipe 28, compressor 29, pipe 39 and hydrogen activator 41 and thence into tube 3, and therethrough into tank 8. Hydrogen or hydrocarbon gases may be delivered from an 70 extraneous source directly through pipe 44 and valve 45 into and through activator 41 into the tube 3 and thence into tank 8. Hydrocarbon liquid may be withdrawn from tank 8 by means of pump 18 and may thereby be delivered through pipe 17 into 75

tube 3 and thence through furnace 1 in contact with the gas delivered through tube 3.

Hydrogen or hydrocarbon gases such as those produced by cracking hydrocarbon materials or uncracked natural gas may be delivered through 5 tube 3 and through tank 8 and may be combined therein with the comparatively heavier hydrocarbon liquid in tank 8 to form gasoline or heavier hydrocarbon liquids.

My new process contemplates maintaining a 10 body of hydrocarbon liquid in a heated condition and bubbling activated hydrogen or hydrocarbon gases through this hydrocarbon liquid, thus effecting a chemical combination between the gases and the liquid. As these gases remain activated 15 for only a short time after contact with molten sodium, I have arranged to bring the molten sodium and gas and hydrocarbon liquid into close contact with each other in order that the gases, after being activated by contact with the sodium, 20 may immediately contact the hydrocarbon liquid with which it is to be united.

As a specific example of one mode of operation of applicant's process, hydrocarbon gases such as those obtained from cracking operations 25 may be heated to a temperature in the neighborhood of 500° F. and while under a pressure of 200 pounds per square inch are contacted with molten sodium and then immediately contacted with fuel oil also at a temperature of approximately 500° F. and under a pressure of 200 pounds per square inch, to produce lighter hydrocarbons, a portion of which boils within the gasoline range.

While the above are conditions under which 35 my process may be carried out, higher and lower temperatures and pressures may be employed, depending upon the charging stock and product desired. In general temperatures within the range of 210° F. and 800° F. and pressures approximating 50 pounds per square inch to 250 pounds per square inch will suffice. Since the hydrocarbon gases remain activated for only a short period of time, the contact time will of necessity be very short.

While I have described in detail a method by which my new process may be carried out, it should be understood that I do not propose to limit myself to these details but expect to broadly claim all of the advantages inherent in my 50 new process.

I claim:

1. The process of combining hydrocarbon liquids with hydrocarbon gases which comprises circulating an endless stream of hydrocarbon 55 liquid, circulating an endless stream of hydrocarbon gas, contacting the two streams at one point and activating the stream of hydrocarbon gas with a catalyst comprising molten sodium in the immediate vicinity of said point to 60 effect combination between said hydrocarbon liquid and said hydrocarbon gas.

2. The process of combining relatively heavy hydrocarbon liquids with hydrocarbon gases which comprises circulating an endless stream 65 of hydrocarbon liquid, contacting said stream with an endless circulating stream of activated hydrocarbon gas to thereby effect combination between said hydrocarbon liquid and said hydrocarbon gas and maintaining said hydrocarbon 70 gas in an activated state at the point of contact of the two streams by effecting said contacting in the presence of a body of molten sodium.

3. The process of combining hydrocarbon liquids with hydrocarbon gases which comprises 75

circulating an endless stream of hydrocarbon liquid, contacting said stream at one point with an endless circulating stream of hydrocarbon gas, activating said stream of hydrocarbon gas by 5 passing the same through a body of molten sodium at substantially the point of contact of the two streams to thereby effect combination between said hydrocarbon liquid and said hydrocarbon gas and withdrawing liquid products from said stream of hydrocarbon liquid after said contact-
10 ing.

4. The process of combining hydrocarbon liquids with hydrocarbon gases which comprises circulating an endless stream of hydrocarbon liquid, contacting said stream at one point with an 15 endless circulating stream of hydrocarbon gas, activating said stream of hydrocarbon gas substantially at the point of contact of the two streams by effecting said contact in the presence

of a body of molten sodium and causing said gas to flow upwardly through said sodium to thereby effect combination between said hydrocarbon liquid and said hydrocarbon gas and withdrawing liquid products from said stream of hydrocarbon liquid after said contacting. 5

5. The process of combining hydrocarbon liquids with hydrocarbon gases which comprises, heating a stream of hydrocarbon gases, heating a stream of hydrocarbon liquids, activating said 10 stream of hydrocarbon gases by bubbling through a mass of molten sodium, contacting said activated hydrocarbon gases and said hydrocarbon liquid in the immediate vicinity of said sodium mass, and heating a portion of said molten sodium by introducing the same into the hydrocarbon gas stream prior to said heating step. 15
